UNITED STATES PATENT OFFICE.

KATHLEEN M. POLHAMUS, OF SOUTH PASADENA, CALIFORNIA.

DESIGN FOR A BONNET.

59,032.

Specification for Design.

Patented Sept. 13, 1921.

Application filed April 11, 1921. Serial No. 460,501. Term of patent 3½ years.

To all whom it may concern:

Be it known that I, KATHLEEN M. POLHAMUS, a citizen of the United States, residing at South Pasadena, in the county of Los Angeles and State of California, have invented a new, original, and ornamental Design for Bonnets, of which the following is a specification, reference being had to the accompanying drawings, forming a part thereof.

Fig. 2 is a side view thereof.

I claim:

The ornamental design for a bonnet, as shown.

Mrs. KATHLEEN M. POLHAMUS.
